VAPORIZER TYPE OIL BURNER

Scott C. Tewar, Burbank, Calif.

Application March 13, 1945, Serial No. 582,498

5 Claims. (Cl. 158—65)

1

The present invention relates to improvements in an oil burner, and it consists of the combinations, constructions and arrangements herein-after described and claimed.

An object of my invention is to provide an oil burner for heating purposes in which the parts are so arranged that when they are properly placed or housed in a space heating unit with an outside stack, a natural air draft is created that carries a flame from the point of combustion around a fuel oil generating tube. This action preheats the fuel oil prior to combustion, vaporizing and gasifying it before it reaches the nozzle. The gas produced from the fuel oil burns in a steady flame.

A further object of my invention is to provide a device of the type described which may be quickly applied to a furnace or other device to be heated. The device makes use of gravity or pressure feeding for the oil. The burner utilizes the power generated from the fuel oil it heats and turns the fuel oil into a gas for causing the burner to function without applying any other auxiliary power to condition or preheat the fuel oil before burning.

Other objects and advantages will appear in the following specification, and the novel features of the device will be particularly pointed out in the appended claims.

My invention is illustrated in the accompanying drawing forming a part of this application, in which:

Figure 1 is a side perspective view of the device;
Figure 2 is a front end perspective view;

Figure 3 is a longitudinal section through the device taken substantially along the line 3—3 of Figure 2; and

Figure 4 is a transverse section taken along the line 4—4 of Figure 3.

While I have shown only the preferred form of my invention, it should be understood that various changes or modifications may be made within the scope of the appended claims without departing from the spirit and scope of the invention.

In carrying out my invention I provide an oil burner having a fire box housing indicated generally at A. The fire box housing has two fire box tube outlets B and C, disposed on opposite sides of the housing A and communicating therewith through openings 1, see Figure 3. A draft tube D is received in the housing A and Figure 3 shows the tube having exterior threads 2 at one end, these threads screwing into interior threads 3 whereby the tube D is secured to the housing A. The tube D has an open entrance end 4 for air.

2

Within the housing A and draft tube D I mount an oil vapor generating tube E of considerably smaller diameter than the tube D. The tube E extends through a bushing 5 mounted in the closed end 6 of the housing A. The front end of the tube E is spaced just inside of the air inlet opening 4 and a coupling 7 connects the front end with a pipe elbow 8. A burner nozzle F is secured to the elbow 8 and has an orifice 9 that faces toward the interior of the tube D and extends partly into the opening 4. It will be noted from Figure 3 that the orifice 9 is positioned under the tube E and above a composition plate 10 that is used to ignite oil held on the plate, the ignited oil creating sufficient heat to cause the generating tube E to vaporize and gasify the fuel oil contained therewithin.

The rear of the tube E has a coupling 11 which connects a pipe 12 to the tube. The pipe, in turn, is connected by means of an elbow 13 to a fuel supply pipe 14. Oil may be fed to the pipe 14 by gravity or under pressure.

From the foregoing description of the various parts of the device, the operation thereof may be readily understood.

The oil burner may be properly placed or housed in a space heating unit that has an outside stack. When starting the operation of the oil burner, the composition clay plate 10 has some drops of oil applied thereto and this is accomplished by opening the valve 15 on the pipe 14 for allowing a small quantity of oil to bleed from the orifice 9 and drop upon the plate 10. The valve is then closed and the oil on the plate is ignited.

The flame from the oil will envelope the end of the generating tube E disposed nearest the coupling 7 and the oil nearest the nozzle F will be vaporized first and will issue from the orifice 9 and become ignited by the flame from the composition plate 10. The natural draft will carry the flame along the outer surface of the generator tube E and will pass out through the tube outlets B and C as shown by the arrows in Figure 1. The flame in passing through the tube D envelopes the tube E and this will soon increase the temperature of the tube E to a point where complete gasifying of the vapor will take place. The gas thus produced from the fuel oil will burn in a steady flame. The size of the flame can be regulated by the amount the valve 15 is opened. As soon as the gas starts to issue from the orifice 9, the operator opens the valve 15 to the desired extent to allow the oil to flow into the vaporizing chamber or tube E.

It is apparent that: (1) the point of combus-

tion or ignition of the fuel oil is directly in front of any fuel oil container, tube or generator so that the fuel is initially vaporized and then gasified; and (2) the natural draft in the burner will carry the flame from the point of combustion along the length of a fuel generator for generating gas from the fuel prior to the gas reaching the jet orifice.

An oil burner using this principle of causing the natural draft to carry the flame from the jet orifice along the fuel generator to be preheated, generates gas from the fuel with practically the same results as the more expensive oil burners that use some sort of mechanical power source for vaporization. Two oil generating tubes can be used if a larger quantity of gas is needed. The generating tubes may be of different sizes and shapes.

The draft tube and fire box are so designed that the heat is confined to a small area through which the fire passes. Any unburned gases escaping from the jet are ignited by the flames before they escape from the fire box. A practically complete combustion of all gases of combustion takes place in the burner unit before the gases reach the space heating unit in which the burner is housed. The device can burn kerosene, distillate or Diesel oil. It will be noted from the drawings that the combined cross-sectional areas of the passageways defined by the outlet tubes B and C is considerably larger than the cross-sectional area of the air inlet 4 of the draft tube D. The combustion chamber is in the fire box housing A, although combustion takes place through the entire burner assembly. The wall of the combustion chamber becomes highly heated from the burning fuel vapor and radiates heat to insure practically complete burning of all gases of combustion in the burner unit. The term "housing," as used in the appended claims, includes both the housing A and the draft tube D.

I claim:

1. An oil burner comprising a housing having an open and a closed end, said housing being unrestricted in the direction of said closed end, outlet tubes communicating with the housing adjacent to the closed end and on opposite sides of the housing, an oil vapor generating tube disposed within and spaced from the housing wall, said tube extending throughout the length of the housing and projecting through the closed housing end, means for feeding oil to the oil vapor generating tube, and a burner jet communicating with the oil vapor generating tube end disposed closest to the open end of the housing, said jet directing a flame into the housing, the housing and outlet tubes creating a natural draft for carrying the flame directly against the oil vapor generating tube and along the length thereof, whereby the fuel in the oil vapor generating tube is vaporized and gasified before reaching the jet.

2. An oil burner comprising a housing having an open and a closed end, said housing being unrestricted in the direction of said closed end, outlet tubes communicating with the housing adjacent to the closed end and on opposite sides of the housing, an oil vapor generating tube disposed within and spaced from the housing wall, said tube extending throughout the length of the housing and projecting through the closed housing end, means for feeding oil to the oil vapor generating tube, a burner jet communicating with the oil vapor generating tube end disposed clos-

est to the housing opening, said jet directing a flame into the housing, the housing and outlet tubes creating a natural draft for carrying the flame directly against the oil vapor generating tube and along the length thereof, whereby the fuel in the oil vapor generating tube is vaporized and gasified before reaching the jet, said jet being positioned under the oil vapor generating tube wall, and a plate placed in the housing directly under the jet and adapted to receive a small fuel portion which may be ignited for initially heating the oil vapor generating tube for vaporizing the fuel oil.

3. In combination, a horizontally-disposed housing having an air inlet end and a closed end, said housing being unrestricted in the direction of said closed end, a pair of vertically-extending outlet tubes communicating with the sides of the housing adjacent to the closed housing end, a tubular oil vaporizer extending longitudinally through the housing from the open housing end and projecting through the closed housing end, a jet communicating with the tubular oil vaporizer end disposed adjacent to the open housing end and being positioned below the tubular oil vaporizer and facing so as to direct a flame into the housing and against the tubular oil vaporizer, and means for feeding oil to the tubular oil vaporizer end projecting through the closed housing end.

4. In combination, a horizontally-disposed housing having an air inlet end and a closed end, said housing being unrestricted in the direction of said closed end, a pair of vertically-extending outlet tubes communicating with the sides of the housing adjacent to the closed housing end, a tubular oil vaporizer extending longitudinally through the housing from the open housing end and projecting through the closed housing end, a jet communicating with the tubular oil vaporizer end disposed adjacent to the open housing end and being positioned below the tubular oil vaporizer and facing so as to direct a flame into the housing, means for feeding oil to the tubular oil vaporizer end projecting through the closed housing end, and an oil-receiving plate placed in the housing and under the jet, and adapted to receive a small fuel portion which may be ignited for initially heating the tubular oil vaporizer for vaporizing the fuel oil.

5. An oil burner comprising a housing closed at one end and having an air entrance at the other end, said housing being unrestricted in the direction of said one end, and a fuel vaporizing tube extending into the housing from the closed end, the front end of the vaporizing tube being turned and having a jet disposed at the air entrance to the housing and facing toward the closed end, said housing having outlet tubes communicating therewith adjacent to the closed end, the combined cross-sectional areas of the passageways of the outlet tubes being considerably larger than the area of the air entrance of the housing, thereby accommodating the gases of combustion as they expand while passing through the housing, the space disposed between the air entrance of the housing and the outlet tubes constituting the combustion chamber whose wall radiates heat during the operation of the burner to insure practically complete burning of all of the gases of combustion within the burner.
